UNITED STATES PATENT OFFICE.

ELMER A. SPERRY, OF CLEVELAND, OHIO.

CENTRIFUGAL MACHINE.

1,048,905.

Specification of Letters Patent. Patented Dec. 31, 1912.

Application filed February 25, 1905. Serial No. 247,236.

To all whom it may concern:

Be it known that I, ELMER A. SPERRY, a citizen of the United States, residing at Cleveland, in the county of Cuyahoga and 5 State of Ohio, have invented new and useful Improvements in Centrifugal Machines; of which the following is a specification.

My invention relates to centrifugal or hydro-extractors, and it specially relates to 10 continuously acting apparatus of this character and consists in means for causing a discharge movement of the materials, especially granular and mobile materials, toward a discharge point and from a point at which the 15 material is delivered within the centrifugal device, and it consists essentially in apparatus designed to bring about this end, the nature and construction of which is fully described herein, and the essential features of 20 novelty pointed out in the claims hereto annexed and forming a part hereof.

The means employed in the present invention are extremely simple, and may be constructed in various forms, and will readily be understood from the drawings herewith, 25 which show a continuous centrifugal apparatus embodying one form of construction which serves to illustrate the action of the device; but the invention should in no wise 30 be limited in its scope to the construction shown in accompanying drawings, in which;

Figure 1 is a vertical section of one form of the apparatus; Fig. 2 is a diagrammatic view of the rotating basket showing a plurality of rotating strippers or ejectors and other details. Fig. 3 is an isolated view of 35 a pair of ejectors of different lengths and angles, showing a power connection; Fig. 4 is a form of ejector with a screw-like blade 40 or blades; Fig. 5 is an alternate form of ejector disk or blade; Fig. 6 illustrates a roller bearing for mounting or journaling the rotating ejector, also other details, together with a hollow form of ejector disk or blade.

A rotating basket of any of the usual forms or constructions is illustrated at 10, supported by the central shaft 11 through the medium of the base plate 12 having radial webs 13 radiating from a central hub 14 45 and keyed and secured to the conical part of the shaft 11. This shaft may protrude from below, or it may depend from the usual bearings and support above, which form is designed to be illustrated in the drawing. The

basket may be straight sided, or the sides 55 may be of any contour. For some purposes, however, it is found preferable to make it of the conical shape illustrated, where it narrows to the discharge end, which may or may not be furnished with the ring 15. In 60 the present instance this ring is shown to have an outward and downward inclined projection or lip. The basket 10 is furnished with the usual perforations, and may or may not be reinforced by other rings 16 as occasion demands. Surrounding the basket is the usual stationary casing 17 supported upon standards or risers 18 of any suitable 65 form. One or more of these risers are furnished with means such, for instance, as the 70 rod or rods 20, the nature and use of which will be described below. The casing 17 terminates below in a channel 21, which for some purposes may be suitably inclined, as shown, and terminate in the duct or discharge nozzle 22. Suitably located with reference to the casing 17 and the channel 21 is a separate compartment 23, the floor 24 of which is considerably inclined, as shown by the dotted lines, and at its lower point 80 communicates with the discharge pipe 25 leading in any direction therefrom, preferably downwardly as illustrated. The inner and lower cavity terminates near the top of the basket, but preferably by an in- 85 turning projection just under the overhanging ring 15. To afford easy access, covers may be used upon these cavities which may inclose the entire apparatus or its outer portion only, which latter arrangement is 90 illustrated in the drawing by the sectional covers 26 which may be furnished with handle 27 and derive their support in any suitable means, as, for instance, the hooks 30 engaging the L-shaped ring or projection 95 31, or they may be still more securely locked in position by any form of joint or tongue and groove, one form of the latter being shown. The apparatus being designed for continuous operation, it is provided with 100 both the induction and eduction apparatus which is adapted to this end. Any form of induction apparatus may be employed, for instance, the feed tube 33 having a receiving belt 34 and a discharging belt or orifice 105 35, and may surround in part the central shaft 11 and be provided with the sleeve 36 which does not necessarily engage the shaft.

The portion of the shaft interior to the tube 33 for some purposes may be provided with the arms 37, for the purpose of agitating or stirring the incoming materials. These arms 5 are shown as being inclined at such an angle as will tend to force the material downwardly within the tube.

Any suitable contour of bottom of basket may be utilized; but a contour having a depression 38 between the hub and periphery is preferred, whereby gravity is made to give its full effect in distributing the material at points near the center where the centrifugal action is weakest, and the upwardly inclined portion at distances more remote from the center where the centrifugal action is more effective.

The discharging apparatus or ejector of the present invention consists of blades in the form of a series of disks, which may be in a plane at right angles to the axis as illustrated in Figs. 1 and 3, or the blade or blades may consist of a series or a continuous spiral or line of blade peripheries, as illustrated in Fig. 4. The disks or blades 40, together with the center stem 41 or shaft, constitute preferably a rotating member, although it is possible that they may be stationary and adjustable from one point to another on the periphery, but their free rotation is desirable and is preferred in the constructions herewith illustrated. Any suitable source of power may be used to rotate this element. In either form, the rotation should be in the same direction as that of the basket. When allowed to rotate as by impingement of the drying material, the center stem 43 may consist of a stationary stud, hollow or otherwise, suitably supported within the stationary portion 44 and about which the sleeve or stem 41 rotates. To facilitate the rotation, this stem is provided with the usual ball or roller bearing arrangement, illustrated at 45 (see Fig. 6), outside of which may be a tight protecting cap 46. A ball-bearing co-operating with the one illustrated at 45 may be utilized at the top of the stem at or near portion 44, which greatly facilitates the ease 50 of rotation. When separate blades are used, as 40, they are threaded upon the central stem 41 in any suitable manner and with any suitable degree of proximity. The means for supporting the portion 44 immediately suspending the rotating member, may be in any suitable form. It is preferable, however, that this device should be adapted for ready removal of the ejector as a whole, such, for instance, as may be secured by sliding the journal portion 47 upwardly and downwardly upon the stem 20, which may be facilitated by the rack teeth 48 and co-operating pinion mounted upon the shaft 49 controlled by the hand wheel 66 50. This piece may be clamped by the han-

dled screw clamp 51. Similarly the stem 52 may be adjusted in or out, or swung within the lateral projection of the part 47, and clamped therein by the screw controlled by the handle 53. We thus see that the rotating member may be lifted in and out of the basket 10 upon the rod 20 or its equivalent. It may also be moved away from or toward the inner face of the basket, and it may be tipped with reference to the vertical plane 75 and is, therefore, virtually universally adjustable. A plurality of rotating members or groups 40 may be used, as illustrated in Fig. 2, adjustable on their vertical stems 20 and lateral stems 52. In this instance, a 80 hoop may be used, illustrated at 54, or its equivalent, for connecting the various supporting arrangements, preferably attached to the parts 44 and 52, so that they may be simultaneously tilted. In this way, after 85 they are loosened by the screw 53, a circumferential movement of the hoop 54 will cause all of the rotating parts to be tilted simultaneously and in the same direction with reference to the plane of action. This hoop 90 may be seen in section in Fig. 1, and also one method of its attachment to the parts 44 and 52 through the arm 55. This constitutes a means for simultaneously moving the plurality of ejectors. In some instances, it is 95 known that the basket in its operation takes on more or less of a tremor or vibration or swinging motion, and for most effective action the ejector should move with the basket, and in some instances it is found 100 preferable to afford a resilient support to the ejector. One form of such support is illustrated in Fig. 6, where the jointed union between the parts 44 and 52 is shown as surrounded by rubber or equivalent bushing 56, 105 affording the required resiliency.

In handling some materials it will be found better to notch the disks with incisions which reach to a greater or less depth. One form of this is illustrated in Fig. 5, the incisions being indicated at 60.

For some purposes, and especially in cases where the depth of the distribution of materials should be controlled and varied, groups of ejectors may be employed with differing 115 angles and with portions of the group shorter (axially), and located in different relative positions to the longer ejector. One such arrangement is shown in Fig. 3, where a view is shown from the interior of the basket 120 looking toward the inner surface of the far side, a section of the bottom 12 being indicated, above which is the basket 10 surmounted at its upper edge by the ring 15 against or near which is located the long and 125 short extractor, the latter being tilted at a greater angle than the first, impinging the material along the upper edge of the basket only. Any want of freedom in rotation of the shorter member, owing to its lesser con- 130

tact with the material and greater angle of action, may be supplied by the power driving connection at the top from any source, as it may consist of the belt pulleys 61 and 62 connected by the belt 63 and so organized as to transmit the rotative effort derived from the longer member to the shorter one, or the belt may be power driven from any suitable source. Means consisting of the pinion 64 and segmental rack teeth 65 are afforded for altering the relative angle of the members of the group, the shorter member swinging about the center 66. The pulley 62 gyrates upon the ball 67 upon the spindle 41 of the short member, the alignment with the pulley 62 being maintained by the flanges through the medium of the elastic belt 63. The bracket 44 may be supported in any manner so as to be adjustable in any of the various manners above described.

For certain purposes it becomes necessary to wash, steam, cook, agitate or otherwise treat the contents of the basket, preferably during the process of spinning or treatment under the centrifugal action. To facilitate this process and to cause it to be very much more effective, it is thought wise to apply the special treatment mentioned through the rotating disks, or blades, but in this instance they are made hollow and suitably apertured for this purpose, inasmuch as these disks continually enter into and are constantly deeply cutting the mass of the substance under treatment, and inasmuch as this requires only slight alteration in the structure of the rotating element. Details have been illustrated in Fig. 6 of one form of the device which may fulfil the double purpose of acting as an ejecting means and at the same time perform the functions of steaming, heating, washing, or the like. Fig. 6 also serves to illustrate not only resilient support, piped connection, but also one form of ball or roller bearing. Upon the exterior of the sleeve 41 are slipped thimbles 70 which may have apertures 71 communicating with the interior of the sleeve 41, which is in turn communicated with the hollow stem 43 by lateral vents 72. Between the lower thimbles 70 and the part 73 is impinged the lower half of the inclosed disk 42-42. These disks are preferably given an inverted spherical "dish" bringing the peripheral edges together at point 74, which edges may be notched as shown at 75 or near the edges apertures may be provided as shown at 76. This description covers each member of the series of pairs of disks 42-42, the interiors of which will be seen to communicate with the pipe 19. Thus it will be seen that a pressure, either negative or positive, of a liquid or gas communicated to pipe 19 finally finds its way through the interior of the hollow disks and discharges or enters at or near their peripheries. To pre-

vent communication with the exterior from the space within the tube 41, a stuffing box is provided which may be of any of the usual forms, for instance, the body 77 contains the packing 78 impinged by follower 79, the lower edge of the body serving to impinge the edges of all of the disks 42 and thimbles 70. The ball bearing at the base of the rotating part is inclosed in the cap 46, the rollers being impinged between the lower race 45 and the upper race 80, the former being supported upon the pin depending from the lower end of the stem 43, and the latter finding its support in the spindle 41 below the projection 73.

Having now described my invention and one method of carrying its essential details into effect, its use and operation will be apparent. It will be assumed that the basket 10 is rotating at a constant speed suited to the special material to be treated or dried. This material in its wet state flows into the tube 33, being urged downwardly by projections 37 of shaft 11 where this is necessary, arriving upon the bottom plate of the basket near the center. It quickly takes up the motion of the moving basket and the centrifugal force carries it outwardly and upwardly on the surface 12 until the peripheral upward bend directs it on to the perforated portion 10 of the basket proper. This basket may receive the usual coverings, differing with different materials, upon which the substance accumulates as the liquids are forcibly ejected, this going on clear around on the interior surface in the lower zone of the conical basket. As the material within the basket is spun at one or more points in its revolution, it encounters the blade or blades or the series of disks 40 upon the stem 41 which is power driven or is given the utmost freedom of rotation through the roller bearings, such as have been illustrated at 45. The periphery of the blade or disks cut into the substance to a greater or less depth and the blades or disks are caused to rotate through the impingement thus secured. This rotation is found to take place with more vigor than would be expected, owing to the fact that the crystals or substance through the intense centrifugal action becomes exceedingly dense and forms a compact mass against the inner wall of the basket, that is, the blade or disk takes on a motion that is in the same direction and a peripheral speed that approximates that of the material within and on the inner wall of the basket; this is especially true with the spiral form. The speed of the blade or blades 40 will at once be seen to be a differential speed, and for some purposes is obviously more suited to the performance of its functions by being thus differential, either if driven through impingement or otherwise. It will be ob-

5 served that the simple cutting of the rotation of the blade or blades or disks into the moist mass as it sweeps past the region of the rotatable member would accomplish
 10 nothing in point of movement or transport of the masses from one point to another. It, however, avails as a means of treatment of the substance constituting the mass, as has been explained in connection with the form of apparatus described in Fig. 6, but
 15 as this is a secondary object, the primal object, namely, that of moving and finally ejecting the dry material is not accomplished if the axis of the rotatable member remains in the plane of the shaft 11, or the plane of parallel radii of the basket. If, however, this axis is tilted out of this plane, even to a very slight degree, in such a manner that its lower end trails with the motion of the basket, so that the portion of the blade or disk which comes next to or is tangential to the inner wall of the revolving basket, or that part of such blade as impinges the material upon the inner wall of the basket, is out of the transverse plane of basket the desired result is brought about.

When the blades are disk-like, as in Fig. 1, it is not necessary to the function that the speed be differential, though usually this is 30 the case, through the imperfect driving secured by impingement as stated. When the relation of angle and speed are as stated, a marked change comes over the drying masses within the basket, and they are found to gradually move upwardly, being dried 35 more and more as they are spread, mobilized and agitated through the action of the series of rotating disks. This gradual yet continuous upward movement of the mass persists 40 until the top of the basket is reached, when it is found to be forced outwardly over the edge and in this manner ejected and removed clear of the basket, being suitably caught as by flying into the outer circular 45 cavity 23, and finally passing out through the tube or tubes 25 provided for this purpose. The reason for the upward movement of the masses will be apparent from Fig. 1. The tilting of the blades or their angle in 50 the region of impingement is such that they enter the masses at a lower point than that at which they leave the masses, this causing a slight lifting or upward movement equal in extent to this elevation of one end of the 55 chord over the other, this chord representing the immersion depth of each sweep of the blade or each disk into the masses. For some conditions or characters of material it may be found preferable to use a plurality 60 of blades or groups of disks rotating upon their axes as illustrated in Fig. 2. When so used, they are adjusted as to height in a certain relation to each other, which, for the best effect, should be a half or a third of 65 the pitch distance between adjacent blades,

as the case may be, dependent upon a number of groups present. The action of such a plurality of groups consists of a slight elevation of the material by each group, such that the blade or disk 40 of the next group 70 will catch and continue the upward movement. The greater the angle of the blade at the point of impingement the more rapidly is the material removed, and the less the angle the longer the material is retained— 75 hence, slower its ejection and the drier the material. The incidental function of this device as an agitator to the mass, thereby greatly facilitates the drying or other treatment, is a very valuable one as it is found to still further facilitate and hasten the action. The action of the hydro-extractor, provided with this device, becomes a continuous one, and the basket requires no stopping or even change in speed while treating 80 a large quantity, even many tons of material. It has been estimated that the increase of capacity of a given centrifugal with granular material is many times the amount of work performed by the old method. 85

Where the masses tend to become hard as they are compacted by the centrifugal action, the notched blade or disk shown in Fig. 3 may be employed. Where it is desirable that the material be thinned down at 90 any point in the basket, as, for instance, in the center of the height of the basket to save undue strains in this portion or at the top of the basket to facilitate the removal of the material at a given point, the arrangement shown in Fig. 3 may be employed, where the material is elevated to a point by the slower process and then removed more rapidly by the rotary ejector which is placed at a greater angle as shown. The liquids are 95 drained in the usual manner by gutter 21, discharge pipe or its equivalent 22. The group of disks may be supported and adjusted by any well known means, one form 100 of which is shown in Figs. 1, 2 and 3, with 105 an alternate form in Fig. 6. The removal 110 of the rotating member as a whole is facilitated by wheel 50 driving a pinion which cooperates with rack 48 upon the stem 20. The tilting action is secured between the stem 12 and the socket 47, as is also the depth to 115 which the disks are forced into the masses of substances contained in the basket, this latter by adjusting the stem 52 inwardly and outwardly from the socket. The screws 51 and 53 serve to clamp the parts into position after adjustment. The angle of the blades is illustrated in Fig. 3 and Fig. 4, and also in Fig. 1, the arrow about the shaft 11 indicating its direction of movement. 120 When it is desired to simultaneously treat the substance as well as eject, the device takes the form illustrated in Fig. 6, where the heating, moistening, or other treatment is in part delivered into the interior masses 125 130

of the material through the disks themselves as they enter the substance. It is designed to use the parts substantially as and in the relation shown. It is apparent, however, 5 that some may be omitted and others may or may not be substituted, and the invention extends to such use.

Having now fully described my invention, what I claim and desire to secure by Letters

10 Patent is:

1. Self discharging centrifugal apparatus comprising a rotating basket, rotatable blades interior to the basket entering the substance to be discharged, the axis of which

15 intersects the axial plane of the basket.

2. Self discharging centrifugal apparatus comprising a rotating basket, rotatable blades interior to the basket entering the substance to be discharged at a plurality of 20 points, and rotating in the same direction as the basket.

3. Self discharging centrifugal apparatus comprising a rotating basket, rotatable blades interior to the basket entering the 25 substance to be discharged at a plurality of points, such points located near each other along a line approximately parallel with the axis of the basket.

4. Self discharging centrifugal apparatus 30 comprising a rotating basket rotatable blades interior to the basket, at an angle to the transverse plane of the basket at the point next adjacent to the wall of the basket, and rotating at a differential speed with said 35 walls.

5. Self discharging centrifugal apparatus comprising a rotating basket, rotatable blades interior to the basket, and at an 40 angle to the transverse plane of the basket 45 at the point next adjacent to the wall of the basket, rotating at a differential speed and in the same direction as the walls.

6. Self discharging centrifugal apparatus comprising a rotating basket, rotatable 45 blades interior to the basket, the blade impinging the side wall of the basket and inclined at such point of impingement at an angle to the transverse plane of the basket and rotating at a peripheral speed differing 50 slightly from that of the basket.

7. Self discharging centrifugal apparatus comprising a rotating basket, rotatable blades interior to the basket and at an angle 55 to the transverse plane of the basket at the point next adjacent to the walls of the basket, and rotating at a differential speed and in the same direction as the walls, the blade being driven through impingement with the material to be discharged while it is acted 60 upon within the basket, and in the same direction therewith.

8. Self discharging centrifugal apparatus comprising a rotating basket a radially adjustable rotatable member interior to the 65 basket having blades entering the substance

to be discharged the axis of which is eccentric to the axis of the basket.

9. Self discharging centrifugal apparatus comprising a rotating basket, universally adjustably supported rotatable member interior to the basket having blades entering the substance to be discharged the axis of 70 which is eccentric to the axis of the basket.

10. Self discharging centrifugal apparatus comprising a rotating basket, resiliently supported rotatable member interior to the basket having blades entering the substance to be discharged the axis of which is eccentric to the axis of the basket. 75

11. Self discharging centrifugal apparatus comprising a rotating basket with inclined peripheral sides rotatable member interior to the basket having blades entering the substance to be discharged the axis of which is laterally tilted out of parallel with 80 the axis of the basket. 85

12. Self discharging centrifugal apparatus comprising a rotating basket with conical sides, rotatable member interior to the basket having blades entering the substance 90 to be discharged the axis of which is out of the plane of parallel radii of the basket.

13. Self discharging centrifugal apparatus comprising a rotating basket, rotatable blades interior to the basket entering the 95 substance to be discharged, the axis of which is laterally tilted out of parallel with the axis of the basket, and a feeding device for the basket.

14. Self discharging centrifugal apparatus comprising a rotating basket, rotatable blades interior to the basket entering the substance to be discharged, the axis of which is laterally tilted out of parallel with the axis of the basket, a feeding device for the 100 basket discharging near the bottom of such basket. 105

15. Self discharging centrifugal apparatus comprising a rotatable basket, rotatable member interior to the basket having blades 110 entering the substance to be discharged, the axis of which is eccentric to the axis of the basket, and means for controlling the temperature of the projections.

16. Self discharging centrifugal apparatus comprising a rotating basket, rotatable member interior to the basket having disk-like hollow projections entering the substance to be discharged, the axis of which is eccentric to the axis of the basket. 115

17. Self discharging centrifugal apparatus comprising a rotating basket, rotatable member interior to the basket having disk-like hollow projections entering the substance to be discharged, the axis of which is 120 eccentric to the axis of the basket, and a stationary means for communication with the interior of the projections.

18. Self discharging centrifugal apparatus comprising a rotating basket, hollow 130

rotatable member interior to the basket having blades entering the substance to be discharged, the axis of which is eccentric to the axis of the basket.

5 19. Self discharging centrifugal apparatus comprising a rotating basket, hollow rotatable member interior to the basket having blades entering the substance to be discharged, the axis of which is eccentric to the 10 axis of the basket, and apertures through the walls of the rotating member.

20. Self discharging centrifugal apparatus comprising a rotating basket rotatable blades interior to the basket entering the substance to be discharged, the axis of which is laterally tilted out of parallel with the axis of the basket, and a feeding device for the basket, and a stirring means for feeding device.

20 21. A continuous centrifugal apparatus comprising a rotating basket, means for feeding the basket and rotary discharging device consisting of a plurality of rotatable blades having an axis to one side of the center and deriving its motion from impingement upon the covering of the inner walls of the basket.

22. A continuous centrifugal apparatus comprising a rotating basket, means for feeding the basket, a rotary discharging device consisting of a plurality of rotatable blades having an axis to one side of the center and deriving its motion from impingement upon the covering of the inner walls of the basket, and a roller bearing for the device.

23. A continuous centrifugal apparatus comprising a rotating basket, means for feeding the basket, a rotary discharging device consisting of a plurality of rotatable blades having an axis to one side of the center and deriving its motion from impingement upon the covering of the inner walls of the basket, a stationary stud and a 45 roller bearing for the device.

24. Self discharging centrifugal apparatus comprising a rotating basket, rotatable blades interior to the basket entering the substance to be discharged, the axis of 50 which intersects the axial plane of the basket, said axis being also eccentric to that of the basket.

25. In a continuous hydro-extractor a discharge apparatus consisting of a rotatable tube surrounding and suitably journaled upon a stationary stud and blades secured to the tube.

26. In a continuous hydro-extractor a discharge apparatus consisting of a rotatable tube surrounding and suitably journaled upon a stationary stud and blades secured to the tube, a cap for the lower end of the tube and roller bearings between it and the stud.

65 27. In a continuous hydro-extractor a dis-

charge apparatus consisting of a rotatable tube surrounding and suitably journaled upon a stationary stud and blades secured to the tube, and means for adjustably supporting the stud.

70

28. Self discharging centrifugal apparatus comprising a rotating basket, rotatable blades interior to the basket entering the substance to be discharged, the axis of which intersects the axial plane of the basket, the 75 said blades having sharp edges.

29. In a continuous hydro-extractor a discharge apparatus consisting of a rotatable tube surrounding and suitably journaled upon a stationary stud and blades secured to the tube, and a stuffing box for the upper end of the tube.

30. Self discharging centrifugal apparatus comprising a rotating basket, having also a gyrating motion and ejecting mechanism operating inferior to the basket, the mounting of the mechanism being such as to follow the gyrations of the basket.

31. Self discharging centrifugal apparatus comprising a rotating basket, rotatable blades interior to the basket entering the substance to be discharged, the axis of which is laterally tilted out of parallel with the axis of the basket, and a plurality of stationary receptacles located outside of basket.

32. In a continuous hydro-extractor a discharge apparatus consisting of a rotatable tube surrounding and suitably journaled upon a stationary stud and hollow disk-like projections secured to the tube.

100

33. In a continuous hydro-extractor a discharge apparatus consisting of a rotatable tube surrounding and suitably journaled upon a stationary stud and hollow disk-like projections secured to the tube, and apertures through the walls of the disks.

34. In a continuous hydro-extractor a discharge apparatus consisting of a rotatable tube surrounding and suitably journaled upon a stationary stud and hollow disk-like 110 projections secured to the tube, and apertures through the walls of the disks, and a stationary piped connection communicating with the interior of the tube and hollow projections.

125

35. In a continuous hydro-extractor a discharge apparatus consisting of a rotatable tube surrounding and suitably journaled upon a hollow stationary stud and secured to the tube, and a pipe connection to the 120 hollow stud.

36. Self discharging centrifugal apparatus comprising a rotating basket, rotatable blades interior to the basket entering the substance to be discharged, the axis of which intersects the axial plane of the basket, and a plurality of stationary receptacles surrounding the basket.

125

37. In a continuous hydro-extractor a discharge apparatus consisting of a rotatable 130

tube, suitably journaled upon a stationary stud, blades, secured to the tube, and a cap for the lower end of the tube.

38. Self discharging centrifugal apparatus comprising a rotating basket, rotatable blades interior to the basket entering the substance to be discharged, the axis of which intersects the axial plane of the basket, and a plurality of stationary receptacles surrounding the basket. 20

39. Continuous centrifugal apparatus comprising a rotating basket, a rotary discharging device for the material which is being treated within the basket, so impinging the material as to cause it to gradually creep 15

upwardly along the inner walls of the basket and to be finally discharged over the upper edge thereof while being held in contact with the said inner walls, the said rotary device deriving its motion from impingement upon the said material within the basket.

In testimony whereof I have hereunto set my hand in presence of two subscribing witnesses.
